UNITED STATES PATENT OFFICE.

RALPH M. LOVEJOY, OF MEREDITH, NEW HAMPSHIRE.

DESIGN FOR A SHOCK-ABSORBER.

54,641.

Specification for Design.

Patented Mar. 9, 1920.

Application filed September 15, 1919. Serial No. 324,033. Term of patent 14 years.

To all whom it may concern:

Be it known that I, RALPH M. LOVEJOY, a citizen of the United States, residing in Meredith, in the county of Belknap and State of New Hampshire, have invented a new, original, and ornamental Design for Shock-Absorbers, of which the following is a specification, reference being had to the accompanying drawing, forming a part thereof.

Figure 1 is a perspective view showing my design for a shock absorber as viewed from one side, looking slightly downwardly upon it.

Fig. 2 is a perspective view of the opposite side of the same looking upwardly at it.

The design resides in the shape and configuration of the casing and the laterally extending arm pivoted to the casing as shown but does not depend upon the particular angular relation assumed by the arm on its pivot with respect to the casing.

I claim—

The ornamental design for a shock absorber as shown in the accompanying drawing and described herein.

RALPH M. LOVEJOY.
